I. S. DICKEN.

HINGE.

APPLICATION FILED SEPT. 29, 1920.

1,392,049.

Patented Sept. 27, 1921.

INVENTOR

ISHAM S. DICKEN,
by Arthur O Eckert ATTORNEY.

UNITED STATES PATENT OFFICE.

ISHAM S. DICKEN, OF ST. LOUIS, MISSOURI, ASSIGNOR OF ONE-HALF TO WILLIAM T. MILES, OF ST. LOUIS, MISSOURI.

HINGE.

1,392,049.

Specification of Letters Patent. Patented Sept. 27, 1921.

Application filed September 29, 1920. Serial No. 413,580.

To all whom it may concern:

Be it known that ISHAM S. DICKEN, a citizen of the United States of America, residing at St. Louis, State of Missouri, has 5 invented certain new and useful Improvements in Hinges, of which the following is a specification.

The object of my invention is to produce a hinge in which the leaves are adjustable 10 relative each other. In the use of a conventional hinge on a heavy door such as that on a refrigerator car since the leaves are not adjustable, when the door becomes wedged or stuck in its casement it is practically impossible to open the door without 15 destroying it. My hinge is particularly adapted for the use on refrigerator cars and the like. By its use the door may be slightly elevated and loosened from its casement.

With the above purpose in view my invention consists in certain novel features of construction and arrangements of parts, as will be hereafter more fully described, 25 pointed out in the claim and illustrated by the accompanying drawings in which:

Figure 1 is a perspective view of the movable leaf and

Fig. 2 is a perspective view of the stationary leaf and

Fig. 3 is a perspective of the pintle holding the stationary and movable leaves of Figs. 1 and 2 in operative positions and

Fig. 4 is a sectional plan of the assembled 35 hinge, the section being taken through the knuckles of the leaves.

Numeral 5 designates the stationary leaf having the holes 6 and the knuckles 7 and 8. In the knuckle 8 is formed a counter 40 sunk portion 9 of the form best illustrated in Fig. 4. In the knuckle 7 is formed a slot 10. Numeral 11 designates a set-screw secured by threaded engagement with the knuckle 7.

Numeral 12 designates a movable leaf having 45 the holes 13 and the knuckle 14 in which is formed the hole 15 extending entirely through the knuckle. The knuckles 7 and 8 are placed in spaced relationship, and the 50 width of the knuckle 14 is of such dimension as to completely occupy the space be-

tween said knuckles 7 and 8. Numeral 16 designates a pintle having a shaft 17 rounded at its external end 18 and having the head 19.

When the movable leaf 12 is positioned 55 so that its knuckle 14 is positioned between the knuckles 7 and 8 the pintle 16 is dropped through the slot 10, the hole 15 and into the counter sunk portion 9 of the knuckle 8. The diameter of the hole 15 is slightly 60 greater than the diameter of the shaft 17 of the pintle 16. By this means the leaves of the hinge are secured in rotative engagement with each other. The counter sunk portion 9 of the knuckle 8 is of the shape of 65 the segment of a sphere of substantially larger radius than the diameter of the shaft 17 of the pintle 16.

The slot 10 in the knuckle 7 is of a width slightly greater than the diameter of the shaft 17 of the pintle 16.

Assuming the stationary leaf 5 secured to the vertical post of the casement of the door of a refrigerator car and assuming that the movable leaf 12 is secured to the door of 75 such a car and that the leaves are held in rotative position by means of the pintle 16, it will be seen that by rotating the set-screw 11 the pintle 16 will be moved longitudinally in the slot 10 and the end 18 rotated in the counter sunk portion 9 of the knuckle 8. By this rotation, the door will be moved upward and rotated slightly above the counter sunk portion 9 of the knuckle 8 of the lower hinge. There will of course be 85 two hinges to the door; that is an upper hinge and a lower hinge.

The weight of the door normally causes the door to sag and this will maintain the pintle in the position against the set-screw 90 shown in Fig. 4.

When the door has been thus moved it will have been loosened from its casement and can be easily opened.

What I claim and mean to secure by Letters Patent is—

In a hinge, a stationary leaf having knuckles formed integral therewith and a slot formed in one of said knuckles, a counter sunk portion formed in the other of 100 said knuckles, a movable leaf having a knuckle with a hole therethrough, a pintle

said pintle passing through the slot in said stationary leaf, the hole in the knuckle of said movable leaf and into the counter sunk portion of the knuckle of said stationary leaf, a set-screw operatively secured to said slotted knuckle so that a rotation of said set-screw will cause a lateral movement of

said pintle in said slotted knuckle and a rotation of the end of said pintle in the counter sunk portion of one of said other 10 knuckles.

In testimony whereof I affix my signature.

ISHAM S. DICKEN.
